UNITED STATES PATENT OFFICE.

FREDRICK W. EAGER, OF WINTHROP, MASSACHUSETTS, ASSIGNOR TO UNITED SHOE MACHINERY COMPANY, OF PATERSON, NEW JERSEY, A CORPORATION OF NEW JERSEY.

HOLDDOWN FOR LASTING-MACHINES.

1,142,152.

Specification of Letters Patent.

Patented June 8, 1915.

Application filed September 27, 1913. Serial No. 792,120.

To all whom it may concern:

Be it known that I, FREDRICK W. EAGER, a citizen of the United States, residing at Winthrop, in the county of Suffolk and State of Massachusetts, have invented certain Improvements in Holddowns for Lasting-Machines, of which the following description, in connection with the accompanying drawings, is a specification, like reference characters on the drawings indicating like parts in the several figures.

This invention relates to lasting machines and particularly to means for holding the work in bed lasting machines.

In lasting shoes upon the commercial bed lasting machines, it is necessary that the shoe be held down firmly upon the toe rest and it is important that the innersole be firmly held at and adjacent to the channel lip at the end of the toe and at the outer or more curved side of the toe because while the upper is being wiped over the edge of the last and over the feather of the innersole the innersole tends to crumple up at the channel or the rib line, or even to be displaced bodily unless it is securely held against such action. The difficulty from crumpling of the innersole has seriously increased within the past few years during which the great advance in the price of leather has obliged manufacturers, in order to keep as near as possible to the former manufacturing cost, to use a thinner innersole or one which is of less firm quality, it having been found that such an innersole will give good satisfaction provided the shoe is properly lasted and welted.

In addition to the difficulties arising from the crumpling up of the innersole at the channel and the consequent displacement of the lip which determines the stitching line by which the welt is attached around the toe, the use of these thinner and more flexible innersoles greatly increases, as would be expected, the liability that the lip or rib will be bent inwardly or overridden in lasting the toe of the shoe so that the upper materials lie upon it and render uncertain or impossible the proper stitching of the upper materials and welt to it. This difficulty is increased by the present use of bulky fabric toe stiffening material in place of the thinner but more expensive sole leather stiffeners. For these reasons it has become increasingly important to provide a sup-

port or abutment for the inner face of the channel lip at the tip of the toe and particularly on the outer side of the toe where is found the "swing" that characterizes distinctively right and left lasts. Furthermore, since the toes of modern right and left lasts are not symmetrical with respect to the longitudinal median line, it becomes necessary in order that the lip of the innersole shall be properly supported that the holding means be capable of adaptation to perform its function on either a right or left toe.

The object of this invention is to provide a simple and effective hold-down device which will be well adapted to meet commercial conditions and which may be employed by the operator without loss of time in adjusting the same, and which, furthermore, will result in increased production and an improvement in the quality of the work turned out.

An important feature of the invention is the provision, in connection with a hold-down finger for engaging the tip of the insole, of a supplementary member or auxiliary finger to bear in a similar manner upon the outer side of the toe, the said member preferably being capable of lateral adjustment without removal and also preferably without the loosening or tightening of its holding mechanism, as, for example, to fit innersoles of different patterns, or to fit either a right or left crooked innersole of the same pattern. Preferably the supplementary holding member comprises an arm pivoted to the finger but adapted to be swung to either side thereof into position to apply pressure to either margin of the innersole; that is, to apply pressure on the outer side of either a right or a left innersole.

In the accompanying drawings,—Figure 1 is a perspective view of the improved hold-down together with the wipers and toe rest of a bed lasting machine; Fig. 2 is a plan view of the hold-down in a modified form in position upon the innersole of a shoe.

At A is shown the forward portion of a toe lasting head of the commercial type of bed lasting machine, such for example as that shown in United States Letters Patent to Brock, No. 1,018,466, granted February 27, 1912. At B is shown a toe rest which sustains the toe portion of a shoe during the

lasting operation. The operating mechanism for the hold-down is substantially similar to that disclosed and fully described in printed British specification No. 19,512/11, 5 to which reference may be had for details not herein given. The post 2 is mounted for vertical movement by means of a treadle, not shown. The head 6 is mounted for rotation on the post 2 and supports a carrier 8 mounted to slide therein transversely of the shoe and having friction means for holding it in any position of adjustment. The inner end of the support 8 carries a headed stud 9 upon which is detachably held a finger 10 by means of a slot 12 provided for the purpose. The finger 10 extends from the ball portion of the shoe, upon which the head of the stud 9 is adapted to bear, to the toe end of the innersole where it engages the lip or 20 rib and supports it and the forepart of the innersole against crumpling or displacement by the overwiping action of the wipers. The finger 10 is formed at its end, or innersole engaging portion, with forwardly facing 25 teeth, as shown in Fig. 1. The finger 10 is provided with a transverse or supplementary pressing member 16 which is preferably formed at its end with teeth facing toward its free end. The member 16 is movably secured 30 to the finger 10 and this connection may be effected in any suitable manner, as by a rivet 17 which will form a friction joint between the finger 10 and the member 16 and permit the same to be adjusted at any desired angle 35 to the finger, or to be swung to the side of the finger opposite to that shown in Fig. 2, for use on a right shoe. If desired, a slot 20 may be provided in either the finger 10 or the member 16, or both, to permit adjustments of the finger and the member 40 relatively to each other for large and small shoes. If desired, a nut or thumb nut 22 may be used in place of the rivet to provide a more ready adjustment of the finger 16 45 respectively to the finger 10.

Having described my invention, what I claim as new and desire to secure by Letters Patent of the United States is:—

1. A hold-down for lasting machines, comprising a member arranged to extend longitudinally of the shoe and to apply pressure to the toe end of the innersole, and a mem- 50

ber arranged to extend on either side thereof alternately into position to engage the inner-sole of either a right shoe or a left shoe at 55 the outer side of the toe.

2. A hold-down for lasting machines, comprising a carrier, a finger 10 secured to the carrier and extending lengthwise of the shoe at right angles to the carrier, and a supplemental finger pivoted to the finger 10 for lateral adjustment to contact with the inner-sole alternatively at either lateral side of the finger 10. 60

3. A hold-down for lasting machines, comprising a member arranged to extend length- 65 wise of the shoe and to apply pressure to the toe end of the innersole at the inner side of the rib, and a member secured to said first member and arranged to be positioned 70 to extend toward either lateral side of said first member into position to engage right and left innersoles adjacent to that portion of the rib which is on the outer side of the toe. 75

4. A hold-down for lasting machines, comprising, in combination, with a hold-down finger for engaging the tip of the toe of the innersole of a shoe, of a supplementary member to bear in a similar manner upon 80 the outer side of the toe of the innersole, and a connection between said fingers permitting relative bodily adjustment of said fingers endwise to adapt them to fit different shapes of innersoles, substantially as de- 85 scribed. 95

5. A hold-down for lasting machines, comprising a member arranged to extend length- 90 wise of the shoe and to apply pressure to the toe end of the innersole at the inner side of the rib, a second member connected thereto and arranged at an angle to said first member to bear in a similar manner upon the outer side of the toe of the innersole, 95 said members being slotted, and a bolt en- gaging said slots and arranged to hold said members adjustably together. 95

In testimony whereof I have signed my name to this specification in the presence of two subscribing witnesses.

FREDRICK W. EAGER.

Copies of this patent may be obtained for five cents each, by addressing the "Commissioner of Patents Washington, D. C."

It is hereby certified that in Letters Patent No. 1,142,152, granted June 8, 1915, upon the application of Fredrick W. Eager, of Winthrop, Massachusetts, for an improvement in "Holddowns for Lasting-Machines," an error appears in the printed specification requiring correction as follows: Page 2, line 54, claim 1, for the word "alternately" read *alternatively*; and that the said Letters Patent should be read with this correction therein that the same may conform to the record of the case in the Patent Office.

Signed and sealed this 1st day of February, A. D., 1916.
